UNITED STATES PATENT OFFICE.

WILLIAM W. WETHERLA, OF CHICAGO, ILLINOIS.

AUTOMATIC HEAT-REGULATING INCUBATOR.

938,190.

Specification of Letters Patent.

Patented Oct. 26, 1909.

Application filed December 19, 1908. Serial No. 468,339.

To all whom it may concern:

Be it known that I, WILLIAM W. WETHERLA, a citizen of the United States, residing at Chicago, in the county of Cook and State 5 of Illinois, have invented certain new and useful Improvements in Automatic Heat-Regulating Incubators, of which the following is a specification.

The present invention relates particularly 10 to incubators of the class applicable for infants and bacteriological use; and the essential object of this improved device is to utilize suitable automatic electrical heating means in connection with the incubator for 15 maintaining a constant and uniform temperature therein.

The invention consists in the features of construction and combination of parts hereinafter described and claimed.

20 In the drawings, Figure 1 is a sectional elevation of this improved automatic heat regulating incubator; Fig. 2 a top or plan view of the electrical controlling apparatus on top of the incubator; Fig. 3 a diagrammatic view of the electrical circuit employed 25 therein; Fig. 4 a section, taken on line 4—4 of Fig. 1; Fig. 5 a section, taken on line 5—5 of Fig. 1, looking in the direction of the arrow; and Fig. 6 a sectional elevation of 30 the thermometer and attachments employed in connection with the incubator.

The body of this improved incubator is preferably of square or rectangular formation, and is usually made from metal suitably lined with asbestos to prevent the radiation 35 of heat generated therein, and comprises, as indicated in Fig. 1, a hinged top or cover 7 provided in its center with a piece of glass 8; and the incubator frame as 40 a whole is mounted upon supporting standards or uprights 9, as usual. A transverse support 10 is positioned between said standards, and has companion brackets or arms 11 secured centrally on its under side for 45 receiving and retaining a movable drawer 12 which normally contains moisture; and as the air is admitted therein it travels upwardly through wire gauze 13 spread over a central opening in the transverse support 50 10. As shown, a plurality of incandescent lamps 14 are positioned directly above the wire gauze, which in common use are of 4 candle power and six in number, and are suitably incased within a housing 15 having 55 a series of slotted openings 16 formed in its top for permitting the admitted air,

after it has been somewhat heated, to escape into the body of the incubator. As the admitted air travels upwardly, it contacts the transversely disposed gauze netting 17, 60 which usually extends from side to side of the frame, and above said netting, as indicated, is a wire basket 18 of sufficient size to receive an infant. A wire screening 19 is positioned along the front side of the incubator body to protect the lower end of the thermometer 20 which is inserted through the upper wall of the incubator body; and upon its upper end, as particularly illustrated in Fig. 6, is an elongated adjustable 70 screw 21 having a platinum tip 22 projecting downwardly therefrom into an upper mercury chamber 23, which in turn is in communication with a lower mercury chamber 24. As it is important that this thermometer 75 be extremely sensitive to the temperature generated within the incubator body, a small quantity of ether is used therein. The adjustable screw 21 is entered through a collar 21^a, which in turn is screw-threaded onto an 80 elongated sleeve 21^b formed of suitable conducting metal, which collar extends downwardly and is surrounded by a metallic strip 21^c. This strip in turn communicates with suitable wiring, hereinafter described. 85

On the top of the incubator and at one side thereof is placed an electric controlling mechanism, which comprises a pair of main feed wires 25 connected to lamps 14 in the body of the incubator through a switch, 90 which, in this case, is in the form of a mercury cup 26. A hard rubber disk 27, located upon the upper end of the thermostat, has attached thereto a wire 28 leading from a binding post 29 to the mercury in the bottom 95 of the mercury chamber 24, and from a binding post 30 a wire 31 leads through a resistance coil 35 to an electromagnet 32. A wire 31^a leads from the electromagnet and is connected to a main feed wire 25^a. The wire 100 28, above referred to, leading to the bottom of the mercury chamber, is in communication with a feed wire 25, thus establishing, when a connection is made between the platinum tip located in the thermostat and the 105 mercury, a current which will energize the magnet 32. As the magnet 32 is actuated, it will cause the arm 33 to rise, breaking the connection in the mercury cup 26 and stopping the current from flowing there- 110 through to the lamps 14. When, however, the temperature in the incubator is cooled

sufficient to draw the mercury away from the platinum tip 32, the connection to the magnet 32 will be broken, allowing the arm 33 to fall establishing connections through the 5 mercury cup 26 to the lamps, thus supplying more heat to the interior of the incubator body. A wire 31^b leads through a switch, which acts in conjunction with a lamp 36 which is used for the purpose of lighting the 10 interior of the incubator. This lamp can, of course, be operated at any time and is not dependent upon the electrical connection above referred to.

The operation of the electrical controlling 15 apparatus is as follows: When the lights 14 are in use, the current is conducted from the main feed wire 25, through the mercury cups 26, thence into the incubator to the lamps 14. When, however, the heat generated 20 therefrom is sufficient to act on the thermostat and raise the mercury to a sufficient height therein to establish a connection between the mercury and the platinum tip 22, the current is shunted and passes 25 through a wire to the binding post 29 into the wire 28 leading to the bottom of the thermostat, completing a circuit, which acts on the electromagnet 32 to raise the armature 33 and break the connection in the mercury 30 cups 26 and the circuit to the incandescent lamps 14. The current then passes from the electromagnet into the resistance coil 35 and thence to the main feed wires.

A satisfactory temperature for hospital 35 work has been found to be approximately 98½° F., and this improved electrical controlling apparatus has been found to produce excellent results, inasmuch as the electrical current will constantly maintain the 40 desired temperature within the incubator body. The utilization of electrical heating means for this device is highly superior to other heating apparatus, as, for instance, when gas is used, the gas pipe pressure often 45 fluctuates and at times is entirely insufficient and inadequate for the purposes intended.

What I claim as new and desire to secure 50 by Letters Patent is:

1. In an incubator, a thermostat consisting of a glass tube, a column of mercury in said tube, an outer tube surrounding the mercury

tube, ether located in the lower portion of the outer tube, a metallic sleeve on the upper portion of the tube, a collar on the sleeve, an adjustable screw entered into said collar, a platinum tip on the adjustable screw, a wire leading from the bottom of the mercury column, and a wire leading from the elongated metallic sleeve, substantially as described. 60

2. In an incubator, an incubator body provided with incandescent lamps, main feed wires for supplying current to the lamps, a set of mercury cups, an electromagnet for 65 operating said mercury cups, a thermostat connecting with the electromagnet, said thermostat consisting of a glass tube, a column of mercury in said tube, an outer tube surrounding the mercury tube, ether located 70 in the lower portion of the outer tube, a metallic sleeve on the upper portion of the tube, a collar on the sleeve, an adjustable screw entered into said collar, a platinum tip on the adjustable screw, a wire leading 75 from the bottom of the mercury column, and a wire leading from the elongated metallic sleeve, substantially as described.

3. In an incubator, an incubator body provided with incandescent lamps, main feed 80 wires for supplying current to the lamps, a thermostat in connection with one of the main feed wires, said thermostat consisting of a glass tube, a column of mercury in said tube, an outer tube surrounding the mercury 85 tube, ether located in the lower portion of the outer tube, a metallic sleeve on the upper portion of the tube, a collar on the sleeve, an adjustable screw entered into said collar, a platinum tip on the adjustable screw, a wire 90 leading from the bottom of the mercury column, a wire leading from the elongated metallic sleeve, an electromagnet, a connection between the thermostat and the electromagnet, a connection between the other main feed wire and the electromagnet, and a set of mercury cups provided with an arm actuated by the electromagnet, substantially 95 as described.

WILLIAM W. WETHERLA.
